FRIEDRICH RAFFENDORFER, OF GRÜNBERG, SILESIA, GERMANY, ASSIGNOR TO THE FIRM OF HEINRICH C. SOMMER NACHFOLGER, OF DUSSELDORF, GERMANY.

BLOW-OFF VALVE FOR STEAM-HEATED APPARATUS AND THE LIKE.

1,079,663.

Specification of Letters Patent.

Patented Nov. 25, 1913.

Application filed December 19, 1911. Serial No. 666,714.

To all whom it may concern:

Be it known that I, FRIEDRICH RAFFENDORFER, subject of the German Emperor, residing at Grünberg, Silesia, Germany, have ⁵ invented new and useful Improvements in Blow-Off Valves for Steam-Heated Apparatus and the like, of which the following is a specification.

My invention relates to blow-off valves, ¹⁰ having a spiral drainage duct, for steam-heated apparatus and the like, and a primary object is to provide an improved valve of this type which can be regulated within wider limits than those known heretofore. ¹⁵ To these ends, in contradistinction to known valves of this type, the spiral duct in my valve which conducts away the water of condensation enlarges in section toward its discharge outlet. ²⁰ Further my improved blow-off valve comprises not only a special valve, whereby increased capability of regulation of the outflow of the water of condensation is obtained, but also an additional valve suitably ²⁵ united with the said special valve and serving to quickly blow off the water while the steam-heated apparatus is being preliminarily heated by the steam.

One illustrative embodiment of the invention and a modification thereof are represented in vertical section by way of example in the accompanying drawing, which shows one form of my improved blow-off valve.

Referring to the drawing, the numeral 1 ³⁰ designates the casing in which is located the fitting 2 which is provided with a screw-thread 3 which, throughout its length, engages the casing 1. The groove between the convolutions of the screw thread 3 are ³⁵ of increasing depth thereby forming a spiral duct 4, the cross section of which increases from the upper end of the fitting to the lower end thereof.

The fitting 2 has at the top an annular ⁴⁰ groove 5 and is formed above it as a closure plate 6 which fits the casing and is provided with perforations 7. The fitting 2 has in the middle a longitudinal bore 8 which enlarges conically at the top at 9 and at the bottom ⁵⁰ at 10.

The casing is bored cylindrically above the plate 6 and has a lateral branch pipe 11 for admitting the water of condensation. The plate 12 can be moved in the casing by means ⁵⁵ of the screw-threaded spindle 13. The plate

12 has holes 14 passing through it. The screw-threaded spindle 13 can be conveniently adjusted by the hand-wheel 18 whose rotation can be checked by a catch 15.

The bore 8 can be closed below by a screw-threaded spindle 16. This end of the bore is opened only when the total water of condensation is to be rapidly blown off during the preliminary warming.

The water of condensation enters through ⁶⁰ the branch 11. According to the height which the plate 12 is lifted for the time being, the water of condensation passes through a space of smaller or larger cross-section between the plate or valve disk 12 ⁶⁵ and the plate or seat 6 into the duct 4. That the connection with the central channel 8 is also established is of no importance because this is generally closed by the spindle 16. The water of condensation issues at 17. The ⁷⁰ holes 14 in the valve disk 12 also establish a connection between the admission pipe 11 and the middle channel 8 when this valve is closed. Thus when the valve 12 is closed, the pipe 11 can be directly connected with ⁷⁵ the discharge pipe 17 by simply opening the valve 16. By means of the holes 14 a connection between the pipe 11 and the spiral duct 4 is also established when the valve 12 is lifted a distance such that it lies below the ⁸⁰ end of the pipe 11.

I claim:

1. In a blow-off valve for steam-heated apparatus, the combination, with a casing having an inlet at one end and an outlet at the other end thereof, of a fitting therein bearing against the walls of the casing, said fitting having a spiral groove in the periphery thereof forming with the walls of the casing a duct, of a comparatively small ⁹⁰ cross-section, that cross-section increasing from the inlet end of the fitting toward the outlet end.

2. In a blow-off valve for steam-heated apparatus, the combination, with a casing having an inlet at one end and an outlet at the other end thereof, of a fitting therein bearing against the walls of the casing, said fitting having a spiral groove in the periphery thereof forming with the walls of the ¹⁰⁰ casing a duct, of a comparatively small cross-section, that cross-section increasing from the inlet end of the fitting toward the outlet end, the said fitting having a longitudinal central bore, a valve disk for closing ¹⁰⁵ 110

the inlet end of said bore, and a valve disk for closing the outlet end of the same.

3. In a blow-off valve for steam-heated apparatus, the combination, with a casing 5 having an inlet at one end and an outlet at the other end thereof, of a fitting therein bearing against the walls of the casing, said fitting having a spiral groove in the periphery thereof forming with the walls of the 10 casing a duct, of a comparatively small cross-section, that cross-section increasing from the inlet end of the fitting toward the outlet end, the said duct being in open communication with the said outlet, the said fitting having one or more holes in the inlet end thereof communicating with said duct 15 and having a longitudinal bore, a valve disk for closing the inlet end of said bore and a valve disk for closing the outlet end of the 20 same.

4. In a blow-off valve for steam-heated apparatus, the combination, with a casing having an inlet at one end and an outlet at the other end thereof, of a fitting therein

bearing against the walls of the casing, said 25 fitting having a spiral groove in the periphery thereof forming with the walls of the casing a duct, of a comparatively small cross-section, that cross-section increasing from the inlet end of the fitting toward the outlet end, the said duct being in open communication with the said outlet, the said fitting having one or more holes in the inlet end thereof communicating with said duct 30 and having a longitudinal bore, a valve disk for closing the inlet end of said bore and a valve disk for closing the outlet end of the same, the former valve disk having one or more holes through the same leading to the said bore. 35

40 In testimony whereof I have signed my name to this specification in the presence of two subscribing witnesses.

FRIEDRICH RAFFENSDORFER.
